US0D1079658S

(12) **United States Design Patent** (10) **Patent No.:** **US D1,079,658 S**
(45) **Date of Patent:** **** Jun. 17, 2025**

(54) **DATA CABLE**

(71) Applicant: **XIEXUN ELECTRONIC(JIAN) CO., LTD**, Jian (CN)

(72) Inventors: **Huazhong Liu**, Jian (CN); **Huibin Chen**, Jian (CN); **Yanfeng Chen**, Jian (CN)

(73) Assignee: **XIEXUN ELECTRONIC(JIAN) CO., LTD**, Jian (CN)

(**) Term: **15 Years**

(21) Appl. No.: **29/925,870**

(22) Filed: **Jan. 26, 2024**

(30) **Foreign Application Priority Data**

Aug. 14, 2023 (CN) 202330518186.X

(51) **LOC (15) Cl.** **13-03**

(52) **U.S. Cl.**

USPC **D13/153**

(58) **Field of Classification Search**

USPC D13/153, 133, 151, 154, 147; D14/433

CPC ... H01R 13/03; H01R 13/7175; H01R 13/514

See application file for complete search history.

(57) **CLAIM**

The ornamental design for a data cable, as shown and described.

DESCRIPTION

FIG. 1 is a top, front, right side perspective view of a data cable showing our new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view of the data cable; and,

FIG. 8 is an enlarged bottom plan view of the data cable. The broken lines shown in the drawings depict portions of the data cable that form no part of the claimed design.

1 Claim, 7 Drawing Sheets
